CARD HOLDER FOR SHOE RACKS

Filed May 9, 1929

INVENTOR
Harvey L. Glidden
By his Attorney,
Harold M. Davis

UNITED STATES PATENT OFFICE

HARVEY L. GLIDDEN, OF LEXINGTON, MASSACHUSETTS, ASSIGNOR TO UNITED SHOE MACHINERY CORPORATION, OF PATERSON, NEW JERSEY, A CORPORATION OF NEW JERSEY

CARD HOLDER FOR SHOE RACKS

Application filed May 9, 1929. Serial No. 361,664.

This invention relates to card holders for shoe racks and is herein illustrated as embodied in a rack of a type which is commonly used for carrying shoes from one part of a factory to another and for the storage of shoes during and between shoemaking operations. It is to be understood, however, that this invention is not limited to racks of the type referred to but is adapted to use in connection with other devices.

In most shoe factories it is customary to transport shoes from place to place by means of racks which are provided with shoe-supporting members and which are mounted upon casters so that they can be readily moved about the factory. To facilitate the routing of shoes carried by such racks in order that the shoes may be presented for the performance of various shoemaking operations in predetermined sequence and to assist in ascertaining the progress of the shoes through the factory, the racks are provided with numbers. In addition to numbering the racks, upon occasion it is desirable in some way to indicate that a certain lot of shoes should be given precedence over others and, consequently, the racks carrying such shoes are marked "Special", or "Rush", or some other appropriate word. Cards bearing such numbers or words are usually detachably held upon upper portions of the racks so as to be conspicuously exposed.

The card-holding devices heretofore used in shoe factories for the purposes above set forth have not been entirely satisfactory. Some of them are of such construction that they become readily displaced or broken, or are necessarily so located that they do not display the cards held as conspicuously as is desirable, or are difficult of access, thereby wasting the time of the operator in positioning the cards. In other instances, they are objectionable in that they present sharp or projecting portions which catch in the clothing of operators handling the racks or subject such operators to injury.

In view of the foregoing, it is an object of the present invention to provide an improved card holder for shoe racks which, while retaining the advantages of such card holders

as heretofore constructed, will be simple and durable in construction, safe to use, easy to operate and one which at all times will serve to hold cards in such manner that they can readily be seen. To this end there is provided a novel card holder consisting in a supporting member having a card-receiving slot therein and a retaining member comprising a plate formed of resilient material secured to the supporting member and having a free end extending into the slot for holding a card in position in the slot. Preferably and as shown, the supporting member forms part of the frame at the upper portion of a shoe rack and is provided with two parallel slots in which are received legs of a U-shaped plate, formed of spring metal, the neck portion of which is secured to the supporting member at a point between the slots. It will be seen that this device is simple in construction, is one which is not likely to get out of order, and is one in which there are no projecting parts which would be likely to scratch or cut a workman or to catch in his clothing. Furthermore, the device which can be used either for numbered cards or for "rush" cards, or both, serves to secure cards positioned therein in such manner that they will extend above the upper surface of the supporting member where they are readily visible.

The above-mentioned and other features of the invention including certain details of construction and combinations of parts will now be described with reference to the accompanying drawings, in which

Fig. 1 illustrates a portion of a shoe rack provided with a card holder according to the invention;

Fig. 2 is a perspective view of the hand-rail of a shoe rack, having a card holder incorporated therein; and

Fig. 3 is a cross-section through the hand-rail, showing details of the retaining member and slots.

The invention is shown as embodied in a shoe rack of the type disclosed in United States Letters Patent No. 1,687,930, granted October 16, 1928, upon an application filed in the name of W. E. Coombes, to which

reference may be had for a complete description of the construction and arrangement of parts. The upper portion of such rack, which is herein disclosed in Fig. 1, 5 comprises steel frame members 10 and a wooden shelf 12 having shoe-supporting members 14. The upper portions of the frame members 10 at each end of the rack are provided with wooden hand-rails 16 which are commonly gripped by an operator in moving the rack from one place to another. Each of the hand-rails 16 which 10 constitute card-supporting members, best shown in Figs. 2 and 3, are provided with two parallel, spaced slots 18, which may be 15 produced by means of a saw or a routing tool. These slots are of sufficient width easily to receive pieces of stiff cardboard or cards, such as a card 20, and are of sufficient depth so that a card, when resting upon the bottom of a slot, will extend into the supporting member or hand-rail 16 far enough so that the card will normally be held in a substantially vertical position.

20 In order to prevent cards from being accidentally displaced or removed from the slots but at the same time to permit their removal when desired, yielding means has been provided for retaining such cards in the slots. This means preferably comprises a plate 22 formed of spring metal and bent into the form of an inverted U, the depending legs 24 of which are inserted in the slots 18 respectively and the neck portion of which is secured by escutcheon pins 26 to the hand-rail 16 at points between the slots. The free ends of the plate 22 forming the legs 24 normally extend close to or, as shown in Fig. 3, into engagement with the outer walls of the slots 18 in which they are positioned. These legs constitute springs which serve to press cards positioned in the slots against the outer walls of the slots.

In the operation of the device a card, such 45 as card 20 (Fig. 3), is inserted in one of the slots 18 and is pressed downwardly against the spring action of the leg 24 until the card rests upon the bottom of the slot. The leg 24 operates to press the card against the outer wall of the slot and retain it in substantially vertical position, with the greater portion of the card extending above the upper surface of the hand-rail.

By the use of holders constructed as above 50 described cards bearing numbers or other symbols may be readily seen. Where such holders are utilized in shoe racks in the manner above set forth it is possible to ascertain at a glance just where a rack bearing a given number is located with the result that it is possible readily to follow the progress of the corresponding lot of shoes through a shoe factory.

Having described my invention what I

claim as new and desire to secure by Letters Patent of the United States is:—

1. A card holder for shoe racks comprising a supporting member having a pair of parallel slots and a plate formed of resilient material secured to the supporting member and having leg portions which extend into the slots in position to force against the walls of the slots cards inserted in the respective slots. 75

2. A card holder for shoe racks comprising a supporting member having therein a plurality of parallel slots and a plate secured to the supporting member at a point between the slots and having free end portions which are located in the slots in position to engage cards inserted in the slots between said end portions and the walls of the slots. 80

3. A card holder for shoe racks comprising a supporting member having a pair of slots 85 therein and a plate secured to the supporting member between the slots and having resilient end portions which extend into the slots for engaging cards inserted in the slots between said end portions and the walls of the slots. 85

4. A card holder for shoe racks comprising a supporting member having therein a plurality of parallel slots for receiving cards and a card-retaining member comprising a plate bent into the form of a U the neck portion of which is secured to the supporting member between the slots and the legs of which are positioned in the slots and normally extend toward the outer walls thereof. 95

In testimony whereof I have signed my name to this specification.

HARVEY L. GLIDDEN.
